UNITED STATES PATENT OFFICE.

FRANK J. LAHER, OF SEATTLE, WASHINGTON.

MEANS FOR SUPPORTING BUMPERS ON AUTO CHASSIS.

Application filed December 22, 1920. Serial No. 432,578.

To all whom it may concern:

Be it known that I, FRANK J. LAHER, a citizen of the United States, a resident of the city of Seattle, county of King, and 5 State of Washington, have invented a certain new and useful Improvement in Means for Supporting Bumpers on Auto Chassis, of which the following is a specification.

The object of my invention is to provide 10 simple and inexpensive brackets which may readily be mounted on the hounds or side bars of an auto chassis to serve as supports for a bumper, and supporting the latter in correct position.

15 The front ends of the hounds of an auto chassis provide convenient supports on which to mount the bumper, but since such ends are usually built more or less on lines curved in a vertical plane, it would require 20 special supporting elements, or brackets for the different designs of auto chassis, unless some type of bumper-supporting means be provided which may be firmly mounted on any surface curved as mentioned.

25 I attain my object by mounting on the supporting surface of the hounds blocks each having its top and bottom faces concaved, so that the bottom face may be firmly seated on a hound as usually made, and the top face 30 of the block will provide a firm seat for the brackets by which the bumper is supported on the hounds. Preferably I make said blocks of wood so that the curves of 35 their top and bottom faces may be readily worked over by any ordinary tool and changed to that slight degree as will adapt said faces to their purpose.

40 In combination with said blocks I use supporting brackets the lower part of which include vertical and arcuate sections whereby these brackets are adapted to be so supported on said blocks relatively to the curved supporting faces of the hounds as to place the vertical sections of the brackets in proper 45 vertical position. Said brackets are made of suitable metal, and the said arcuate sections describe an arc with a longer radius than the convex top seating faces in said blocks, so that the said arcuate surfaces will always 50 be firmly clamped on the blocks as illustrated diagrammatically in Fig. 6, in the accompanying drawings.

55 My bumper supporting means are particularly designed to provide the proper support for that type of bumper invented by me for which I have filed a companion applica-

tion for Letters Patent of the United States, entitled Bumper for vehicles, which application was filed Dec. 22, 1920, Serial No. 432,577.

60 Referring to the remaining figures in said accompanying drawings,

Fig. 1 shows said type of bumper invented by me, and for the support of which my bumper supporting means herein described 65 are particularly invented by me;

Fig. 2 is a perspective view showing the preferred form in which I construct the brackets of my supporting means;

Fig. 3 shows one end of my said bumper 70 and illustrates diagrammatically how an end is deflected in case of collision between the vehicle and another body;

Fig. 4 illustrates a modification which may be made in the construction of the brackets 75 of my supporting means;

Fig. 5 shows one of the blocks which is to be secured on the hounds of the chassis, and on which the brackets of my supporting means are clamped in place; and

80 Fig. 6 is a diagrammatic view particularly showing the relative curves given the top face of the blocks, and the arcuate sections of the bracket, so that the latter section, and thus the bracket itself, may be firmly 85 clamped down into the concave upper face, or seat, of the block on which the bracket is mounted.

Fig. 1 *a*, *a'* represent the front ends of the hounds or side bars of the auto chassis. 90 Similar portions of the hounds are also shown in Figs. 2, 3, and 4. On each of these ends is mounted a block *b*, preferably of wood, and made with a bottom concave face *c* and a top concave face *d*. The bottom concave face *c* of the block *b* is adapted to be 95 firmly mounted on the curved ends *e* of the hounds. On the blocks *b* are mounted the brackets supporting the extremities of the bumper. These brackets may be made as 100 illustrated in Figs. 2 and 4 but I prefer the construction illustrated in Fig. 2.

105 Referring to the latter figure: The bracket shown consists of an upright part *g* and an angular part *f*, connected by an arcuate section *h*; the part *f* having an angular extension *f'*, which overlaps the part *g*, and said extension *f'* and the part *g* being perforated to receive a clamp-bolt *i*.

110 The arc of the arcuate section *h* has a greater radius than the curve of the upper face *d* of the block *b*. The purpose of such

construction is that when the bracket is mounted on its block it will be firmly held at three points; that is to say, by both the longitudinal extremities of the block *b*, and 5 at the middle of the block, when the arcuate section *h* is drawn firmly down into the concave face *d* of the block by any suitable clamping means, and hence the bracket cannot swivel on the block.

10 The clamping means shown in the drawings consist of a U-bolt *j*, cross-bar *h*, and the nuts *l* threaded on the U-bolt.

The brackets should be made of resilient metal so that the arcuate portions *h* are 15 adapted to be drawn firmly into the concavity *d* of the blocks *b* on which they are seated by said clamping means; and the brackets are made with said arcuate sections *h* in order that the brackets may in all cases 20 be so positioned as to bring the parts *g* substantially vertical, irrespective of the curve which the supporting ends of the hounds may have.

It is necessary that the upright parts *g* of 25 my brackets be vertically positioned, since, as I mentioned, my supporting means were especially invented by me for the purpose of supporting my said special type of bumper illustrated by *m* in Fig. 1, and consisting of 30 a flat resilient bar the two ends of which make an obtuse angle with each other, and have each a return bend with the termini of the ends located close to, and equi-distant from, the middle of the bumper. Since it is 35 necessary that the angular ends of this bumper lie in a plane parallel with the ground, hence said upright parts *g* of the supporting brackets must be supported in a vertical plane.

40 The modification of my bracket illustrated in Fig. 4 comprises an upright part *n*, made with an end *o* having a return bend; the parts *n* and *o* being perforated to receive the clamping-bolt *p*; and the lower end of the 45 part *n* terminates in an arcuate part *q*, which is the equivalent of, and performs the same functions as the arcuate part *h* of my bracket shown in Fig. 2.

The type of bracket shown in Fig. 2, has, 50 for convenience been shown in the illustration of Fig. 1 of the drawings; but, as already stated, I prefer the construction shown in Fig. 2. However, that is merely a matter of personal choice; and indeed I do not 55 wish it to be understood as limiting myself with regard to details of construction.

I claim:

1. Supporting-means of the character described comprising, a block having its bottom face adapted for firmly mounting on the supporting element and its upper face concaved, a bracket comprising an upright part and an arcuate resilient section normally curved to a radius greater than that of the 65 curve of the concaved top of the said block,

means engaging the resilient arcuate section of the bracket and drawing same into contact with the concave surface of the block, and means for fastening the adjacent end of a bumper to said upright part of the bracket. 70

2. Supporting-means of the character described comprising, a block having its bottom face adapted for firmly mounting on the supporting element and its upper face concaved, a bracket made of a bar, flat in cross 75 section, comprising an upright part and an arcuate resilient section normally curved to a radius greater than that of the curve of the concaved top of the said block, and means for fastening the adjacent end of a bumper 80 to said upright part of the bracket.

3. Supporting-means of the character described comprising, a block having its bottom and top faces concaved, a bracket comprising an upright part and an arcuate resilient section normally curved to a radius greater than that of the curve of the concaved top of the said block, and means for attaching the bracket and block to a vehicle frame, said means when in use engaging the 90 normally curved resilient section and drawing same into intimate contact with the concaved top of the block. 85

4. Supporting-means of the character described comprising, a block having its bottom face adapted for firmly mounting on the supporting element and its upper face concaved, a bracket consisting of an upright part and an angular part connected by an arcuate resilient section, the free ends of said 100 parts overlapping one the other.

5. Supporting-means of the character described comprising, a block having its bottom face adapted for firmly mounting on the supporting element and its upper face concaved, a bracket consisting of an upright part and an angular part connected by an arcuate resilient section, the free ends of said 105 parts overlapping one the other, and means for drawing said overlapping parts together. 110

6. Supporting-means of the character described comprising, a block having its bottom face adapted for firmly mounting on the supporting element and its upper face concaved, a bracket consisting of an upright 115 part and an angular part connected by an arcuate resilient section, the free ends of said parts overlapping one the other, and a clamping bolt inserted through the overlapping part. 120

7. Supporting-means of the character described comprising, a block having its bottom face adapted for firmly mounting on the supporting element and its upper face concaved, a bracket made of a flat bar, consisting of an upright part and an angular part connected by an arcuate resilient section, the free ends of said parts overlapping one the other. 125

8. Supporting means of the character de- 130

- scribed comprising, a block having its bottom face adapted for firmly mounting on the supporting element and its upper face concaved, a bracket made of a flat bar, consisting of an upright part and an angular part connected by an arcuate resilient section, the free ends of said parts overlapping one the other, and means for drawing said overlapping parts together.
- 5 10 9. Supporting-means of the character described comprising, a block having its bottom face adapted for firmly mounting on the supporting element and its upper face concaved, a bracket made of a flat bar, consisting of an upright part and an angular part connected by an arcuate resilient section, the free ends of said parts overlapping one the other, and means for drawing said overlapping parts together.
- 15 20 10. Supporting-means of the character described comprising, a block having its bottom face adapted for firmly mounting on the supporting element and its upper face concaved, a bracket made of a flat bar, consisting of an upright part and an angular part connected by an arcuate resilient section, the free ends of said parts overlapping one the other, and means for drawing said overlapping parts together, and means for clamping said supporting-means on the supporting element.

FRANK J. LAHER.
